The ornamental design for a holder for multiple compact disks, as shown and described.

DESCRIPTION

FIG. 1 is a top, front and left side perspective view of a holder for multiple compact disks in a fully closed position showing our new design;

FIG. 2 is a top and front perspective view thereof showing the holder in an open position and each of four lids in a closed position;

FIG. 3 is a top and front perspective view thereof showing the holder in an open position and each of the four lids in an open position;

FIG. 4 is a rear elevational view of FIG. 3;

FIG. 5 is a top plan view of FIG. 3; and,

FIG. 6 is a top and front perspective view showing the holder in an open position with the upper left hand lid open and the other three lids closed.

The broken lines which define the bounds of the claimed design form no part thereof.

The broken lines are for purposes of illustration only and form no part of the claimed design.
